UNITED STATES PATENT OFFICE.

ELIAS VAN DYKE, OF COLUMBUS, OHIO.

REFRIGERATOR.

1,400,643.

Specification of Letters Patent. Patented Dec. 20, 1921.

Application filed September 13, 1919. Serial No. 323,462.

To all whom it may concern:

Be it known that ELIAS VAN DYKE, a citizen of the United States, residing at Columbus, in the county of Franklin and State of Ohio, has invented certain new and useful Improvements in Refrigerators, of which the following is a specification.

This invention relates broadly to refrigerators and has for its general object to provide a refrigerator wherein is embodied improved features of construction for utilizing to a maximum extent the cooling properties of the ice employed, and to prevent the ice from being unduly dissipated by providing the walls of the refrigerator with air spaces, whereby through the medium of the latter the chilled air within the refrigerator will be caused to circulate through said walls and around the food containing compartments of said refrigerator, the invention thus intending to systematize air circulation within the refrigerator so that undue loss of the chilled air will be prevented and the action of said refrigerator rendered more efficient.

Another object of the invention resides in the provision of an improved door structure for refrigerators or ice chests, and wherein the door structure is formed to embody a pair of angularly related sides which are bridged by means of food supporting trays, said sides bearing such relation with each other that when the door proper is open in order that the food upon said trays will be rendered accessible, the back member of the door structure will close the door opening in said refrigerator, so that the chilled compartment of the latter will be maintained at all times in a sealed condition, so that air of higher temperatures will be prevented from entering said compartment and affecting the temperatures of the latter.

A further object of the invention resides in providing the base of the refrigerator with a pan member, which latter being situated immediately beneath the food compartment of said refrigerator is in communication by means of a drain pipe with the ice receiving compartment thereof, through the provision of the pan member, a receptacle is provided for receiving the cool drippings effected by the waste of ice and to thus utilize the said drippings to enhance and maintain the low temperatures of the food compartment.

With these and other objects in view, the

invention accordingly consists in the novel features of construction, combination of elements, and arrangement of parts, herein-after to be fully described and to have the scope thereof pointed out in the appended claims.

In the accompanying drawings, forming a part of this specification, and in which similar characters of reference denote like and corresponding parts:

Figure 1 is a perspective view of the improved refrigerator comprising the present invention.

Fig. 2 is a vertical sectional view taken through the same.

Fig. 3 is a transverse vertical sectional view taken at right angles to the plan of the section disclosed in Fig. 2.

Fig. 4 is a horizontal sectional view, disclosing more particularly the door structure of the refrigerator, and,

Fig. 5 is a detailed perspective view of one of the refrigerator doors.

Referring more particularly to the drawings, the letter A designates the improved refrigerator comprising the present invention in its entirety. This refrigerator in the form shown in the drawings consists of a food compartment B, a supplemental food compartment C, and an ice compartment D. These compartments may be formed by providing the refrigerator with a base 1, which may be provided with depending leg members 2 for the purpose of supporting the base above a suitable floor. Obviously, the leg members may be provided with rollers, if desired. Arising from the base 1 are longitudinally spaced sides 3, a front 4 and a back 5. The sides 3 and the back 5 are preferably formed with double walls, which are spaced apart so as to receive any suitable packing 6, said packing serving in the ordinary capacity common to refrigerators of preventing the ingress of outside temperatures. Likewise, the refrigerator may be formed with a top 7, which is also provided with double walls and an improved packing, which corresponds in utility and purpose to the packing 6.

In addition to the packing 6 and the double wall construction of the refrigerator, which is common in the majority of standard refrigerators, the present invention further provides means for utilizing cooling properties of the ice deposited therein and to render the melting of such ice a compara-

- tively slow process by providing an improved air circulation within the refrigerator around the several compartments thereof.
- 5 To this end, the ice compartment D is preferably defined by means of thin sheet metallic walls 8, which are spaced from the adjoining compartments by one of the sides 3 and the back 5 so as to define air circulating spaces 9 completely around the compartment D, and the front of the latter is preferably closed by means of a packed door 10, whereby ice may be inserted into the compartment. In the rear and side walls of the 10 ice compartment D, there are provided vent openings 11 which enable air within said compartment to circulate into the spaces 9 surrounding the same. Likewise, the compartments B and C are also spaced from the 15 side and back walls 3 and 5 by defining said latter compartments by means of thin sheet metallic walls 12. By thus spacing the walls 12 from the sides and back of the refrigerator, air circulating spaces are defined 20 around the side, back and intervening walls of the compartments C and D which provide air circulating spaces 13, the latter being in direct communication with the spaces 9. The bottom 14 of the compartment B is also 25 spaced from the base 1 so that the air may circulate around the bottom 14. In this manner, it will be obvious that an improved circulation of air is maintained within the refrigerator so that the iced air of the 30 compartment D may be quickly let into the spaces 9 and 13 so as to lower the temperatures of the food compartments B and C and to maintain such compartments at temperatures fairly approximating those of the 35 ice compartment D. In this manner, the temperature of the ice compartment may be uniformly distributed to the food compartments, and hence the maximum value of the ice may be obtained and the products within 40 the compartments B and C may thus receive the benefit of the cool condition of the compartment D without causing waste of ice in the latter. The compartment C may be also equipped with a door 15 so that milk or 45 solids may be placed therein. Spaced members 16 are preferably utilized in securing the walls of said compartments in associated relation with the side and back walls 3 and 5 of the refrigerator.
- 50 To further effect a utilization of the ice within the compartment D, a waste pipe 17 extends from the compartment D to the space between the bottom of the compartment B and the base 1, so that the drippings of said ice compartment may be conducted to this latter space. To cause a flow 55 of the drippings toward the top of the pipe 17, the bottom of the ice compartment is provided with inclined surfaces 18, which 60 converge into the pipe 17, thus leading all 65 water within said ice compartment toward said pipe. A removable pan 19 is located immediately beneath the compartment B and rests upon the base 1 and is so situated as to receive drippings discharged from the 70 waste pipe. Thus the still cool water discharged from the compartment D will be collected within the pan member 19, and since the latter is provided with an open top, said water will serve to cool the surrounding 75 portions of the refrigerator by absorbing the heat thereof. However, the pan member is provided with an outlet 20, whereby when the water within the pan member reaches a certain level, the same will be 80 caused to flow out of the refrigerator and may be suitably collected in the ordinary manner. The arrangement however, is so complete that the water escaping from the outlet 20 will be of very little value in reducing adjacent temperatures. Thus, it will be manifest that through the provision of the air channeled walls of the refrigerator, the food compartments will be maintained at 85 uniform and low temperatures and through 90 the provision of the pan member and associated structure, a very complete utilization of the ice within the compartment D may be had, these features thus tending to provide a refrigerator of marked efficiency and 95 one whose up-keep may be maintained at a reduced cost over structures of common usage.
- It is manifest that ordinary refrigerators are wasteful and inefficient in that when the 100 doors controlling the food compartments thereof are opened, outside air is permitted to rush into the food compartments so that a rise in the temperatures of the latter is bound to follow, and particularly is this true 105 when refrigerators are employed in commercial establishments wherein the opening of the doors continuously obtains. To prevent the rise of the temperatures within the food compartment B, use is made of an improved door structure 21. This door structure, in the present instance, consists of a pair of identically constructed door members 22 which are arranged to coöperate with 110 openings 23 therefor formed in the front 4 115 of the refrigerator. Each of these door members consists of a pair of angularly disposed front and interior sides 24 and 25 respectively, which are arranged to pivot or hinge as at 26 upon their common meeting 120 edge. The side 24 when its door member is closed will coöperate with a strip 27 separating the door members and is rabbeted so that a tight joint may be provided. Likewise, the interior side 25 has its outer edge 125 also rabbeted for similar coöperation with the strip 27 when the door member is open. The sides 24 and 25 are bridged by means of trays 28 which are rigidly carried by said sides and may be of any number or spaced 130

in any suitable manner, said trays being adapted to retain food products placed within the compartment B. It will thus be manifest that when one of the door members is opened, the interior side 25 thereof will oscillate so that the same will engage with the strip 27 and thus seal the opening 23 with which it coöperates. Thus, an operator may proceed to receive products 10 from or place the same on the trays 28 and when engaged in this occupation, the food compartment B will be effectively sealed so that exterior temperatures will be prevented from raising the internal temperatures of 15 the food compartment.

In view of the foregoing description, taken in connection with the accompanying sheets of drawing, it will be apparent that there is provided a refrigerator of considerable utility and one wherein a reduction in 20 ice consumption will obtain. Obviously, this desired result is brought about by the formation of the air courses around the food compartments which communicate with the 25 interior of the ice compartment so that a thorough absorption of heat within the refrigerator may take place, not only in the ice compartment but in the food compartments as well. Also, through the provision 30 of the pan member 19, the drippings of the ice compartment, which are ordinarily allowed to go to waste, are also utilized for heat absorbing purposes and by being situated at the bottom of the refrigerator will 35 serve to block the ingress of heat into the food compartments at this point. Then, through the provision of the peculiarly constructed door members described, the temperature within the food compartment will 40 be maintained even when its doors are open and hence by eliminating undue heat, a saving in ice consumption will of course be obtained.

I claim:

45 1. In a refrigerator, a cabinet including a base having upstanding insulated side walls, a shell having relatively thin walls disposed within said cabinet and supported in spaced

relationship from the walls thereof, whereby air circulating spaces will be produced 50 around said shell, the said shell being further formed to include ice and food compartments, the said ice compartment being provided with apertured walls, whereby air circulation through and between said spaces 55 and ice compartment will be provided, the said food compartment being entirely out of direct communication with said air circulating spaces, and a drain for said ice compartment. 60

2. In a refrigerator, a cabinet including insulated top, bottom and side walls, a shell of thin sheet material arranged to be positioned within said cabinet and supported in spaced relationship from the walls of said 65 cabinet to provide air circulating spaces around said shell, said shell being formed to include a main food compartment and a superposed ice compartment, and the walls of said ice compartment only being aper- 70 tured to establish communication between the interior of said ice compartment and the said air circulating spaces.

3. In a refrigerator, a cabinet including insulated bottom, side and top walls, a shell 75 situated within said cabinet and in spaced relationship from the inner walls thereof whereby air circulating spaces between said shell and cabinet will be produced, said shell being formed to include a main food com- 80 partment and a superposed ice compartment, the walls of the said ice compartment only being apertured to provide communication between said air circulating spaces and the interior of said ice compartment, the said 85 food compartment being out of direct communication with said air circulating spaces, a drip receptacle having an open top arranged to be positioned between the bottom of said shell and said cabinet, the said recep- 90 tacle being in communication with said air circulating spaces, and a drain pipe leading from said ice compartment to said receptacle. 95

In testimony whereof I affix my signature. ELIAS VAN DYKE.
